UNITED STATES PATENT OFFICE.

THOMAS JOSEPH STURTEVANT, OF WELLESLEY, MASSACHUSETTS, ASSIGNEE TO
STURTEVANT MILL COMPANY, A CORPORATION OF MAINE.

SCREENING OR SEPARATING MACHINE.

1,229,810.

Specification of Letters Patent. Patented June 12, 1917.

Application filed November 25, 1916. Serial No. 133,369.

To all whom it may concern:

Be it known that I, THOMAS J. STURTEVANT, a citizen of the United States, residing at Wellesley, in the county of Norfolk 5 and State of Massachusetts, have invented or discovered certain new and useful Improvements in Screening or Separating Machines, of which the following is a specification, reference being had therein to the 10 accompanying drawings.

This invention relates to separating machines with vibrating screens, and has for one of its objects to provide machines of this character which are made in detachable sections or units placed side by side, so that a machine of any desired capacity may be furnished at short notice, each of the detachable sections or units being provided with its own screens and its own jarring 15 mechanism, the jarring devices being all operated from a single source of power. This detachable unit construction is advantageous to the manufacturer in that a machine of any desired capacity may be quickly provided by furnishing any desired number of sections or units, and a large machine may be conveniently transported in sections which can be readily secured together in setting up the machine for use. Moreover the 20 user of a machine comprising a number of complete sections or units may set up a machine of any desired capacity by joining together any desired number of such sections or units. A common distributor will supply 25 the material to be screened by the several units or sections of the separating machine, such distributor preferably consisting of a rotary conveyer mounted in a feed box common to the several sections of the screening 30 or separating machine and provided with means for distributing to each section or unit its proper amount of material. This feed box, as also the rotary conveyer or distributor, may be made in detachable sections 35 corresponding to the sections or units of the separator; or the feeding and distributing parts may be made integral, and in such case may be furnished in lengths corresponding to the number of sections or units of 40 the screening or separating machine which are to be used together.

The jarring driving mechanism for the several separator sections or units, operated from a common source of power, as above referred to, is preferably so constructed and

arranged that the jarring mechanism for any one of several sections or units may be run independently of the other section or sections, so that one or more sections may be run undisturbed while the other section or 60 sections are out of operation.

In the accompanying drawings Figure 1 is a front view of a two-section or two-unit inclined separator embodying the present invention, with the cover of one section or 65 unit in raised position, and Fig. 2 is a broken out side view of the same. Fig. 3 is an end view of the two-unit separator looking from the bottom of Fig. 1. Figs. 4 and 5 are somewhat diagrammatic views 70 illustrating preferred forms of driving connections for the rotary shafts of the jarring mechanisms of the sections or units of the separator. Fig. 6 is a rear view of the top part of a two-section separator provided 75 with a sectional feed box, and Fig. 7 is an end elevation of one unit of the sectional feed box.

Referring to the drawings, 12 denotes the casings of the units of the sectional inclined 80 separator, these casings having complete side parts so that the chambers of the adjoining units or sections are fully divided from each other, each casing thus having its own screening or separating chamber. The sections or units 12 are detachably secured together by means of bolts 10 passing through bracing sleeves 11 interposed between the adjacent sides of the sections or units, as more clearly shown in Fig. 3. Each separator section or unit is provided with a movable cover 13 which is preferably hinged at its top so that it may be lifted, as more clearly shown in Fig. 2, when access to the chamber of a section or unit is desired. The operating portion of the jarring mechanism of each section or unit is mounted on its hinged cover and may be of any desired construction. This operating mechanism, as herein shown, is similar to that shown and described in the Sturtevant U. S. Patents Nos. 1,035,262 and 1,114,064, and comprises rotating shafts 14 mounted on standards fixed to the covers 13, and provided with arms 15 carrying rollers 16 which lift pivoted hammers 17 and which hammers, when released from said rollers, strike on the jarring posts 18. Each screen section is provided with a non-vibrating coarse or scalper screen 19 and a vibrated fine screen 20 below said 110

coarse or scalper screen. The screen clothing of the scalper screen is preferably placed on top of the screen frame and the screen clothing of the fine screen on the bottom of its frame. This construction provides a very considerable space between the screen clothing of the two screens, which is desirable. The vibrating screen 20 is sustained by spring supports 21 beneath which are located stops 22 which limit the downward movements of the vibrating screen, these spring supports and stops being preferably located at the sides of the screen, as clearly shown in Fig. 3. The vibrating screens 20 are provided with cross plates 23 on which are mounted sockets 24 which receive the lower ends of the jarring posts 18 passing loosely through sleeves 25 mounted on cross plates 26 with which the scalper screen 19 is provided.

Mounted at the upper end of the inclined separator sections or units is a feed box 27 in which is journaled a shaft 28 provided with a screw conveyer 29 which distributes the material to be screened or separated and which material is supplied to said feed box from an opening or hopper located at 30 at one end of said feed box at the point where said feed box overhangs the separator, so that the material supplied to the screens will fully cover the same laterally at the upper ends thereof. This feed box and the rotary conveyer or distributor which is mounted therein are common to the several sections or units of the separator so as to supply material to all of the same, such material passing over an adjustable feed plate 31 having an inclined upper edge which is highest at the end of the feed box 30 where the material enters. The feed box is provided in front with a hinged door or cover 32 which, when unbolted, may be raised for the convenient insertion of the conveyer shaft and its bearings 28 which latter are held in place by screws or bolts 28^b, said feed box having at its ends removable slides 33 held in place by the door or cover 32 and which may be taken out when the conveyer shaft and its bearings are to be removed or inserted. The feed box is preferably provided at its rear side with a hinged door 34, and each casing, affording a screening chamber, is also preferably provided at its upper end with a hinged door 35 which may be opened to afford access to said screening chamber, as for the insertion or removal of the screens.

The feed box is preferably removably bolted to the casing sections or units and 60 may be made in one part, as shown in Fig. 1, of a suitable length to supply material to a plurality of screen sections or units; or this feed box may be made in sections, as shown in Figs. 6 and 7, approximately 65 corresponding in length to the width of the

sections or units of the screen or separator. In such case the contiguous parts of said screen sections are provided with flanges 36 for the reception of bolts by which said screen sections may be detachably secured together. In order to enable the conveyer shaft and its bearings to be conveniently removed from or inserted into the front of the feed box in this sectional construction of feed box just referred to, the said feed box will be provided at its front with removable standards or bracing parts 27^a which may be taken out when the hinged door 32 is lifted for the insertion or removal of the conveyer and the feed shaft 28. Also the conveyer shaft and screw conveyer may be made in one part, as shown in Fig. 1, or said shaft and its attached conveyer may be made in detachable parts corresponding in length to the width of the detachable casing sections, one part for each section or unit of the screening or separating machine.

The particular construction of feed box and conveyer or distributor herein shown and described is, however, not claimed in 90 this case, the same being included in my application No. 136,552, filed December 12, 1916.

The screens 19 and 20 are preferably provided at their edges with upwardly extending yielding flanges 37 bearing against the inside walls of the casings 12 so as to prevent the material being screened from passing over the edges of the screens; and the screen frames will also preferably be provided at their sides with inclined deflectors 38 which will cause the material passing down the screens to be diverted on to the wire screen clothing.

In lifting the hinged covers 13 for the separator sections or units it is desirable that the belts by which the shafts 14 are driven should not be disturbed, or at least that it should not be necessary to remove any of said belts, and to this end the present invention provides such an arrangement of driving pulleys and belts that said covers 13 may be lifted and carry with them all the mechanisms thereon, but without disturbing any of the said belts otherwise than by slackening one or more of the same. In the arrangement of this driving mechanism for the shafts 14, shown in Figs. 1 and 4, the pulley 39 on the conveyer shaft 28 is belted to a pulley 40 on an upper shaft 14 which is provided with a pulley 41 belted to a pulley 42 on a lower shaft 14. The upper shaft 14 is provided with a second pulley 43 which is belted to a pulley 44 on a shaft 45 journaled in suitable brackets 46 fixed to the top of the screen frame or casing 12, this shaft 45 being provided with a second pulley 47 belted to a pulley 48 on the upper shaft 14 of the adjoining screen section or unit, said last-named shaft being provided with a 130

5 pulley 49 belted to a pulley 50 on the lower shaft 14 of the second section or unit. From this construction it will be understood that the driving connections between the pulley 39 and the several shafts 14 of the 10 separator sections or units will not be disturbed when either of the covers for the separator sections or units are lifted, but that only a slackening of one or more of the connecting belts will occur when said covers are lifted, so that the running of any section having an unlifted cover may continue undisturbed when the cover of any of the other sections farther from the source of power, is 15 lifted.

10 In the arrangement of the parts of the driving mechanism for the shafts 14 shown in Fig. 5, the pulley 40^a may be belted to the pulley 39 on the conveyer shaft, said pulley 20 being mounted on a shaft 45^a which will be sustained in stationary supports on the screen frames or casing parts, this shaft 45^a being provided with pulleys 51 belted to pulleys 52 on the upper shafts 14 which are 25 provided with pulleys 53 belted to pulleys 54 on the lower shafts 14; and this arrangement of driving mechanism can be used with any desired number of screen sections or units, as will be understood.

30 By removing or slackening the belt connecting the pulleys 47 and 48, in the driving arrangement shown in Figs. 1 and 4, the left hand unit of the separator may be run undisturbed and independently of the right hand unit or section; and by removing or slackening any of the belts connecting the pulleys 51 and 52, in the driving arrangement shown in Fig. 5, any one or more of several separator sections or units may be 40 run undisturbed and independently of the other sections or units, as will be readily understood.

45 The inclined backs or bottoms 35 of the separator sections or units are preferably arranged at a somewhat steeper angle than the screens of the inclined separator. These inclined backs or bottoms are permanent parts of the screen casings and have no doors or openings, which would be of no practical use in this sectional separator construction. The screen casings, including their inclined bottoms, are sustained in inclined positions by the framework or supports 56.

55 This invention is not to be understood as being limited to the details herein shown and described, as these may be varied widely, within the province of mechanical skill, without departing from the scope and gist of the invention.

60 Having thus described my invention I claim and desire to secure by Letters Patent:

65 1. In a vibrating separator, the combination with a plurality of inclined screen sections or units arranged side by side and detachably secured together, said sections or

units being individually complete, having its own casing and jarring mechanism and being provided with inclined screens, of a feed box and a conveyer or distributer mounted at the upper ends of said inclined screen 70 sections or units and common to them all, so as to supply and distribute material to be screened to all of said sections or units.

2. In a vibrating separator, the combination with a plurality of inclined screen sections or units arranged side by side and detachably secured together, said sections or units being each individually complete, having its own casing and jarring mechanism and being provided with inclined screens, 75 of a feed box and a conveyer or distributer mounted at the upper ends of said inclined screen sections or units and common to them all, so as to supply and distribute material to be screened to all of said sections or 80 units, each screen section or unit being provided with a hinged cover, jarring operating mechanism mounted on said cover, and a common source of power from which the jarring mechanisms for the several screen 85 sections or units are operated.

3. In a vibrating screening or separating machine, the combination with a plurality of complete screen sections or units arranged side by side and detachably secured together, 95 each casing of a screen section affording a complete compartment, inclined screens in said compartments, and a screen jarring mechanism for each of said sections or units, of a feed box and distributer common to the 100 several screen sections or units and adapted to supply and distribute material to them all, said feed box being formed in sections corresponding to the sections or units of the separator.

4. In a vibrating screening or separating machine, the combination with a plurality of screen sections or units arranged side by side and detachably secured together, each casing of a screen section affording a complete compartment, inclined screens in said compartments, and a screen jarring mechanism for each section or unit, of a feed box 110 and distributer common to the several screen sections or units and adapted to supply and distribute material to them all, said feed box and distributer being formed in sections corresponding to the sections or units of the separator.

5. In an inclined separator, the combination with a plurality of screen sections or units arranged side by side and detachably secured together, each of said sections or units having a complete casing and being provided with screens and with a hinged 120 cover, of means, extending within the casings of said sections or units, for jarring said screens, jarring operating mechanism mounted on the said cover and comprising 125 rotary shafts, and a driving mechanism for 130

- 5 said shafts so arranged that either of the covers of the sectional separator may be raised without lifting the others or without removing the power connections for their 5 jarring operating mechanisms.
6. In an inclined separator, the combination with a plurality of screen sections or units arranged side by side and detachably secured together, each of said sections or 10 units having a complete casing and being provided with screens and with a hinged cover, of means, extending within the casings of said sections or units, for jarring said screens, jarring operating mechanism 15 mounted on the said covers and comprising rotary shafts, and a driving mechanism for said shafts so arranged that either of the covers of the sectional separator may be raised without lifting the others or without 20 removing the power connections for their jarring operating mechanisms, said driving mechanism comprising pulleys mounted on a fixed part of the machine and belted to and from pulleys mounted on said shafts.
- 25 7. In an inclined separator, the combination with a plurality of screen sections or units arranged side by side and detachably secured together, each of said sections or 30 units having its own complete casing and being provided with screens and with a hinged cover, of means, extending within the casings of said sections or units, for jarring said screens, jarring operating mechanism mounted on the said covers and comprising 35 rotary shafts, a driving mechanism for said shafts so arranged that either of the covers of the sectional separator may be raised without lifting the others or without 40 removing the power connections for their jarring operating mechanisms, said driving mechanism comprising pulleys mounted on a fixed part of the machine and belted to

and from pulleys mounted on said shafts, and a common source of power from which the driving mechanism of all of the sections 45 or units are operated.

8. In a separator, the combination with a plurality of screen sections comprising complete casing parts detachably secured together and having suitable covers, each of 50 said sections being provided with its own screens, means, extending through said covers into said casing parts, for jarring said screens, jarring operating mechanism mounted on said covers and comprising rotary shafts, and a common driving mechanism for all of said shafts so constructed and arranged that the operation of the jarring mechanism of one section may be suspended without disturbing the operation of 55 the other section or sections nearer to the source of power.

9. In a vibrating separator, the combination with a plurality of screen sections or units arranged side by side and detachably secured together and each having a complete casing and being provided with its own screens and jarring mechanism, so as to be complete in itself, a common source of power from which the jarring mechanisms of the 70 several screen sections or units are operated, and driving connections between the several sections or units, so that the jarring mechanism of one section or unit is driven from the jarring mechanism of the adjoining section or unit. 75

10. A screen for use in an inclined separator provided at the side portions of its frame with upwardly extending yielding flanges to bear against the inside walls of 80 the separator casing.

In testimony whereof I affix my signature.

THOMAS JOSEPH STURTEVANT.
